Inventor:

David B. Ellis

United States Patent Office.

DAVID B. ELLIS, OF YPSILANTI, MICHIGAN.

Letters Patent No. 70,821, dated November 12, 1867

IMPROVEMENT IN WHEEL-BARROWS.

The Schedule referred to in these Letters Patent and making part of the same.

TO ALL WHOM IT MAY CONCERN:

Be it known that I, DAVID B. ELLIS, of the city of Ypsilanti, county of Washtenaw, and State of Michigan, have invented a new and improved Brace to the Body and Legs of the Wheel-Barrow; and I do hereby declare that the following is a full and exact description of the said invention.

The nature of my invention consists in a brace running from each end of the forward cross or bed-piece of the body of the wheel-barrow diagonally to the lower end of the leg of the barrow on the opposite side, such braces crossing each other; reference being had to the annexed drawings, making a part of this specification, in which—

Figure 1 is a perspective view of a barrow with one brace attached, and

Figure 2 is a perspective view of the two braces.

A represents the arms to the body; B represents the bed-pieces; C represents the union or double brace; D represents the wheel; E represents the legs with braces attached.

What I claim as my invention, is—

The diagonal brace, bracing and strengthening both the body and legs of the barrow against lateral and perpendicular strain and pressure, substantially as described.

DAVID B. ELLIS.
